UNITED STATES PATENT OFFICE.

JULIUS M. ULRICH, OF GREENWICH, CONNECTICUT, ASSIGNOR OF ONE-HALF TO WILLIAM RAHR, JR., OF MANITOWOC, WISCONSIN.

GAS-ENGINE.

1,019,563.

Specification of Letters Patent.

Patented Mar. 5, 1912.

Application filed August 14, 1906. Serial No. 330,577

To all whom it may concern:

Be it known that I, JULIUS M. ULRICH, a citizen of the United States, residing in the city of Greenwich, county of Fairfield, State of Connecticut, have invented a new and useful Gas-Engine, of which the following is a specification.

My present invention relates to two-cycle gas engines and one of the main objects 10 thereof is to eliminate any gasoline gas being taken into or discharged from the crank case of the engine.

Another object of my present invention is to produce a novel construction of a gasoline engine in which the fuel is not formed or used until after the completion of the compression stroke in the crank case and the feed supply is acquired under compression or forced air circulation.

Another object of my invention is to produce a construction in which there is no possibility of back firing into the crank case and consequent stopping of the engine.

Another object of my invention is to produce a construction in which there is no possibility of the flooding of gasoline vapor into the crank casing and thus prevent the cutting of the bearing parts owing to the oil being thinned by the gasoline.

Another object of my present invention is to produce a construction in which the highest speed of the engine may be maintained owing to the production of a proper mixture of gasoline and air instead of a mixture of air, gasoline and oil.

Another object of my invention is to produce a novel construction of a carbureter in which the valve, which controls the admission of fuel thereinto, is controlled by the air compressed in the crank case passing through the carbureter.

My invention further consists of a novel construction of a valve which automatically controls the admission of air to the carbureter.

It further consists of other novel features of construction, all as will be hereinafter fully set forth.

In order to illustrate my invention, I have shown one embodiment thereof which has been found in practice to give good and satisfactory results, although it is to be understood that the instrumentalities of which my invention consists may be variously arranged and organized and that my invention

is not limited to the exact arrangement and organization of instrumentalities as herein shown.

Figure 1 represents a side elevation partly in section of a two-cycle gas engine embodying my invention. Fig. 2 represents a longitudinal section of the distributor valve. Fig. 3 represents a section on line $x-x$ of Fig. 2. Fig. 4 represents a section on line $y-y$ of Fig. 2.

Similar numerals of reference indicate corresponding parts in the figures.

Referring to the drawings:—1 designates the engine or cylinder casing having a combustion chamber 2 in which is adapted to 70 travel a piston 3 to which is secured in the usual manner, as at 4, a connecting-rod 5, which is connected with the driving shaft 6 in the usual manner, in order to actuate the same, said shaft being located in a crank 75 chamber 7.

10 designates a gear mounted on the shaft 6 which meshes with an idler 11, said idler 11 meshing with a gear 12 mounted on a shaft 13.

14 designates a rotary distributor valve mounted on the shaft 13 and adapted to control the entrance and discharge of air from the atmosphere to the crank chamber and from the crank chamber through the carbureter to the cylinder compression chamber 2. The valve 14 comprises a plurality of segments 15 and 16 through which extends an air passage or port 17, said passage or port passing through the diametrical axis of the valve. The valve 14 engages the valve bushing 18 which is located in the valve casing 19. The segment 15 is provided with apertures or recesses 20 from which extend the seats 21. The segment 16 is provided in a similar manner with apertures or recesses 22 from which extend the seats 23, it being noted that the apertures and seats in one segment are diametrically opposite the apertures and seats in the other segment 100 and that in the present instance the seats are shown as having a smaller diameter than the apertures.

24 designate pins or rods which pass through the shaft 13 and engage the seats 105 21 and 23 respectively.

25 designate springs located in the apertures 20 and interposed between the segment 15 and the shaft 13. 26 designate similar springs located in the apertures 22 and in-

- terposed between the segment 16 and the shaft 13, said springs 25 and 26 causing said segments to engage the valve bushing 18. The segments 15 and 16 may be suitably cored if desired although this is not essential under all conditions.
- 27 designates the air inlet which communicates by means of ports 28 and 29 and passage 17 with the crank chamber 7.
- 10 30 designates a port through which the air is discharged from the crank chamber 7, the air passing through said port 30, passage 17 and port 31 into the carbureter mixing or commingling chamber 32.
- 15 33 designates a throttle valve mounted within the carbureter casing 34, said valve being provided with a handle 35 whereby the same may be manually actuated.
- 20 36 designates the fuel inlet which leads to the float chamber 37.
- 38 designates the inlet casing having a feed passage 39 therethrough, it being noted that the casing 38 is bent upwardly and adapted to receive at its upper end a disk valve 40 which is movably mounted on a needle valve 41, the upper end of which is guided in a sleeve or tube 42, which has threaded or other engagement with the carbureter casing and provided with an actuating handle 43.
- 44 designates a spring interposed between the end of the sleeve 42 and the disk valve 40.
- The needle valve 41 is provided with an actuating handle 60 at its outer end and its inner end is adapted to engage a valve seat 45 and thus regulate the entrance of fuel through the feed inlet 39. The feed inlet 39 has at its upper end a plurality of passages or ports 46 which lead through the closed upper end of the casing 38, said ports in the present instance being shown as diverging from the feed inlet 39.
- 47 designates a by-pass leading from the carbureter chamber 32 and opening into the upper portion of the float chamber 37, said by-pass being provided with a manually actuated valve 48 whereby the air pressure may be regulated as desired.
- 50 49 designates a plunger for priming the float in the float chamber 37.
- 50 designates the cylinder inlet port through which the explosive mixture passes to the combustion chamber 2.
- 55 51 and 52 designate exhaust ports leading from the chamber 2 to the exhaust passage 53.
- 54 designates a spark plug carried at the upper end of the cylinder 1 in the usual manner and constitutes the sparking or ignition mechanism for the explosive mixture.
- 60 55 designates a deflector mounted on the piston 3 to deflect the gas in an upward direction.
- 65 The crank casing 7 is provided with arms

or brackets 56 in order that the same may be secured to a suitable support by means of any desired fastening devices.

57 designates an aperture through the casing contiguous the crank chamber 7.

58 designates an oil drain cock.

The operation is as follows:—Assuming that the piston is at the top of its stroke and traveling toward the crank chamber, as the piston moves downwardly, the air in the crank chamber 7 is compressed. The compression of air in the crank chamber 7 continues until the piston opens the port 50 at which time owing to the manner in which the distributor valve 14 is driven, the passage 17 will register with ports 30 and 31 and the compressed air passes through said ports and passage into the carbureter chamber 32, it being understood that the throttle valve 33 is open at this time. As the compressed air passes through the carbureter chamber 32, it causes the disk valve 40 to be raised and a desired amount of gasoline is withdrawn, said valve 40 rising and falling according to the speed of the engine and thus the amount of gasoline which is withdrawn will depend upon the speed of the engine. The explosive mixture formed by the air and gasoline passes from the carbureter through port 50 into the explosion or combustion chamber 2 and drives out the waste products of combustion from the previous explosion which are discharged through ports 51 and 52 into the exhaust passage 53. The distributor valve 14 continues to rotate and closes the ports 30 and 31. The piston now travels upwardly and a vacuum is formed in the crank chamber. As this vacuum is being formed, the members 15 and 16 of the distributor are maintained against the valve walls until the vacuum is released due to the passage 17 of the distributor valve 14 coming into register with the ports 28 and 29 whereupon the air is drawn from the air inlet 27 through said ports 28 and 29, and passage 17 into the crank chamber 7. When the engine runs at normal speed, the valve 40 remains unseated and fuel is admitted through the passage 39 under the float feed system. When the engine stops the spring 44 will cause the disk valve 40 to be positively seated and no flooding of gasoline into the carbureter mixing chamber 32 can take place.

The throttle valve 33 is so located that when it is closed no pressure is exerted on the supply valve 40 or the needle valve 41, in other words, pressure by throttling is retained in the crank chamber.

If any pressure is exerted on the supply valve 40 or needle valve 41, the valve 48 may be regulated until the pressure is the same in the float chamber 37 as it is in the carbureter chamber 32. It will thus be evident that the inlet port 50 leading from

the carbureter to the combustion chamber must open in unison with the supply ports 30 and 31.

- I am enabled by my novel construction to 5 construct the crank casing of comparatively light material since the liability of explosions firing back thereinto is eliminated, and the amount of oil which it is necessary to employ is reduced to a minimum.
- 10 It will be apparent to those skilled in the art that in my present construction of carbureter, the same embodies a combined float and valve feed.

It will now be apparent from the foregoing 15 that I have produced a novel and useful construction of a two cycle gas engine which embodies the features of advantage enumerated as desirable in the statement of invention and the above description and while 20 I have, in the present instance, shown and described the preferred embodiment thereof, it is to be understood that it is susceptible of modification in various particulars without departing from the spirit and scope of 25 the invention or sacrificing any of its advantages.

Having thus described my invention, what I claim as new and desire to secure by Letters Patent, is:—

- 30 1. In a two-cycle gas engine, in combination with the combustion chamber and the crank chamber thereof, a carbureter communicating with said chambers, a driving shaft, and rotary means actuated thereby for controlling the discharge of air from said crank chamber to said carbureter and the admission of air to said crank chamber.
2. In a two-cycle gas engine, in combination with the combustion chamber and the 40 crank chamber thereof, a carbureter communicating with said chambers, a driving shaft,

and a distributor valve operatively connected therewith and adapted to admit air to the crank chamber at a predetermined time and to permit on the completion of the compression stroke the discharge of air from said crank chamber to said carbureter.

3. In a two-cycle gas engine, in combination with the combustion and crank chamber thereof, a carbureter communicating with 45 said chambers, a driving shaft, and a rotary distributor valve having a port therethrough and operatively connected with said shaft, there being ports for the admission of air to said crank chamber and the discharge of 50 air from said crank chamber to said combustion chamber adapted to register with said distributor port and there being an inlet port communicating with the atmosphere and controlled by said valve.

4. In a two cycle gas engine, the combination with a casing forming the combustion and crank chamber thereof, a carbureter communicating with said chambers, a driving shaft, valve mechanism having a port 55 therethrough operatively connected with said shaft and controlling the delivery of air from the crank chamber to the carbureter, said casing having ports for the admission of air to said crank chamber and the 60 discharge of air from said crank chamber to said combustion chamber and adapted to register with the port of said valve mechanism, and said casing ports including an inlet port communicating with the crank 65 chamber and with the atmosphere and controlled by said valve mechanism.

JULIUS M. ULRICH.
